UNITED STATES PATENT OFFICE.

HARRY SADDLEMIRE, OF CENTRAL BRIDGE, NEW YORK.

SHIELD.

1,318,600.

Specification of Letters Patent.

Patented Oct. 14, 1919.

Application filed November 20, 1918. Serial No. 263,365.

To all whom it may concern:

Be it known that I, HARRY SADDLEMIRE, a citizen of the United States, residing at Central Bridge, in the county of Schoharie, 5 and State of New York, have invented certain new and useful Improvements in Shields, of which the following is a specification.

This invention relates to certain new and 10 useful improvements in body shields and has for its primary object the provision of a shield adapted to be worn by soldiers as a protection against bullets or bayonet thrusts.

Another object of the invention is to so 15 construct the shield that portions thereof will be movable to permit bending of the body when the shield is secured in position.

Another object of the invention is to construct the shield of a plurality of sections 20 including an intermediate cushioning section adapted to absorb the shock caused by the impact of bullets or bayonet thrusts against the outer section of the shield.

A still further object of the invention resides 25 in the peculiar manner of securing the hingedly connected sections of the shield together so that it will be impossible for a bullet or the like to pass between the connected edges of these sections.

30 A still further object of the invention resides in the provision of means for securely and comfortably attaching the shield to the body of the wearer.

Other objects and advantages of the invention 35 will be more readily understood from the following description and drawings wherein I have illustrated the invention in its preferred embodiment and in which drawings:

40 Figure 1 is a view showing in front elevation, a shield constructed in accordance with my invention.

Fig. 2 is a vertical sectional view taken on the line 2—2 of Fig. 1.

45 Fig. 3 is a view taken on line 3—3 of Fig. 1.

The shield, in the preferred embodiment shown, consists of an outer section 1, an inner section 2, and an intermediate section 3, secured together by rivets 4 or other fastening means. The outer and inner sections of this shield are substantially duplicate in construction and preferably are of the shape 50 shown in Fig. 1.

55 The outer section is composed of a plurality of plates comprising an upper main

plate 5 a lower plate 6, and an intermediate plate 7 having its upper and lower edges overlapping the corresponding edges of the plates 5 and 6. The overlapping edges of 60 these plates are cut out as indicated at 8 to provide a neat joint showing therebetween and are connected for swinging movement by suitable hinges 9 which are so arranged as to permit outward swinging movement 65 of each plate. This manner of hinging the plates of the section together is of advantage in that it permits the body of the wearer to be bent readily whenever desired and in this connection it is also pointed out that the 70 edges of the plates are made overlapping in order to prevent the formation of direct passages between these edges when the plates are in angular relation to one another as when bending the body and thus the 75 possibility of a bullet passing between the edges of these plates is obviated.

The inner section 2 is composed of a plurality of plates 10, 11 and 12 which are identical in construction to the plates 5, 6 and 80 7 and have their corresponding edges overlapped in the same manner. It will be noted in this connection that it is unnecessary to hinge the plates 10, 11 and 12 together owing to the fact that each of these plates is 85 riveted to the corresponding plate of the section 1 and is adapted to move or swing in conjunction therewith.

The intermediate section 3 secured between the outer and inner sections is preferably composed of cork though any other compressible material may be used. This intermediate section as clearly shown in Fig. 2 is made in separate pieces arranged between opposing plates of the inner and outer 95 sections and spaced apart to provide intervening spaces of sufficient area to permit free swinging movement of the overlapping edges of the outer and inner sections. As clearly shown in Fig. 2, the intermediate, 100 outer, and inner sections are all secured together by means of the rivets 4 previously mentioned and consequently when the lower plates 6 and 7 of the outer section are swung outwardly as when bending the body it will 105 be obvious that the plates 11 and 12 of the inner section will move in conjunction therewith, the overlapping edges of these hinged plates being so arranged as to prevent the formation of any direct crevices therebetween.

To provide for attaching the shield in po-

sition the upper main plate of one of the sections, preferably the outer section 1 is provided at its upper edge with a pair of shoulder engaging supports 13. These supporting elements 13 are curved to extend to one side of the shield and may be padded on the under surface as indicated at 14 for engagement with the shoulders of the wearer to conform to which the shoulder engaging elements 13 are curved throughout their length. Vertical straps 15 adapted to extend along the back or sides of the wearer are secured at their upper ends to these shoulder engaging supports and at their lower ends to a waist encircling strap 16. The ends of this strap 16 are secured to the vertical edges of the body portion of the shield in any suitable manner and is provided with an adjusting buckle 17 whereby the strap 20 may be tightened about the waist.

From the foregoing it will be evident that I have provided an improved form of shield which may be comfortably secured upon the body of the wearer and will serve as an effective barrier against bullets or bayonet thrusts. The manner of connecting the plates of the outer and inner sections of the shield will permit the body of the wearer to be readily bent when desired and at the same time will prevent the possibility of bullets passing between the connected edges of the plates when the latter are in angular relation to one another. It will be furthermore noted that as the intermediate section 3 is composed of cork or other compressible material, the outer section of the shield will be permitted to have a slight inward movement under heavy impact and the cushioning effect thus obtained obviously will lessen 40 the shock to the wearer.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent, is:—

1. A shield comprising outer and inner sections, each of which consists of a plurality of plates having the corresponding edges thereof overlapping, the plates of one section being hinged together and the plates of the remaining section being secured to said hinged plates to move in conjunction therewith.

2. A shield comprising an outer and inner section each of which consists of a plurality of relatively movable plates having their

corresponding edges overlapping, and a compressible section secured between the outer and inner sections and forming a cushioning medium therebetween. 65

3. A shield comprising outer and inner sections each of which consists of a plurality of plates having the corresponding edges thereof overlapping, the plates of one section being hinged together and the plates of the remaining sections secured to said hinged plates to move in conjunction therewith, and an intermediate section comprising a plurality of compressible pads arranged between the opposing plates of the outer and inner sections and spaced apart to permit movement of the overlapping edges of said plates. 70 75

4. A shield comprising outer and inner sections, each of which consists of a plurality of plates, the plates of one section being hinged together and the plates of the remaining section being secured to said hinged plates to move in unison therewith. 80

5. A shield comprising outer and inner sections each of which consists of a plurality of plates having the corresponding edges thereof overlapping, the plates of one section being hinged together and the plates of the remaining sections being secured to said hinged plates to move in conjunction therewith, and an intermediate section comprising a plurality of compressible pads arranged between the opposing plates of the outer and inner sections and spaced apart to permit movement of the overlapping edges of said plates. 90 95

6. A shield comprising outer and inner sections, each of which consists of a plurality of plates having the corresponding edges thereof overlapping, the plates of one section being hinged together and the plates of the remaining sections being secured to said hinged plates to move in conjunction therewith, and a compressible section secured between the outer and inner sections and forming a cushioning medium therebetween. 100 105

7. A shield comprising a plurality of plates, hingedly mounted upon each other, each plate having a portion thereof adjacent its edge reduced to form a comparatively thin flange, the flanges thus formed on the plates overlapping to provide joints of the plates to prevent direct passages therethrough, whereby the plates will overlap each other and provide even inner and outer surfaces thereupon. 110 115

In testimony whereof I affix my signature 120 in presence of two witnesses.

HARRY SADDLEMIRE.
